UNITED STATES PATENT OFFICE.

WILLIAM GATES, OF NEW HAVEN, AND FRANK W. BOTTUME, OF WALLINGFORD, CONNECTICUT; SAID FRANK W. BOTTUME ASSIGNOR OF ONE-HALF OF THE WHOLE RIGHT TO MARCUS S. BOTTUME, OF MONTOWESE, CONNECTICUT.

CURTAIN-FASTENER.

1,233,216.

Specification of Letters Patent. Patented July 10, 1917.

Application filed November 6, 1916. Serial No. 129,644.

To all whom it may concern:

Be it known that we, (1) WILLIAM GATES and (2) FRANK W. BOTTUME, citizens of the United States, residing at (1) New Haven, (2) Wallingford, county of New Haven, State of Connecticut, have invented an Improvement in Curtain-Fasteners, of which the following is a specification.

This invention relates generally to fasteners, with more particular reference to devices for detachably securing the curtains or "flaps" of vehicle tops to the body of the vehicle and to each other, although it will be apparent that devices embodying our invention are adapted for many other different uses. Particularly in the case of a vehicle, it is well known that the so-called top should not only be easily and readily "put up" and "taken down," it often being most desirable to perform the former operation in the shortest possible period of time, but it is of course to be desired the top when in use be dependably secured and present a sightly appearance.

Heretofore, it has been the most general practice to employ what are known as eye-fasteners, one of the parts being provided with an eye through which is passed a centrally pivoted elongated metal button on the other member, the button being turned through an arc of about 90° to effect a clasp in a common and well-known manner. While this is doubtless a very simple and convenient form of fastening device, it is subject to the objections that due to the constant vibrations of the vehicle the button is likely to become loose on its pivot and is not infrequently jarred to "open" position, permitting separation of the connected parts, to say nothing of producing an annoying "rattle."

The object of the present invention is the provision of what for the purposes of this description we shall term a curtain fastener which is comparatively simple in construction and inexpensive to manufacture,

yet one which may be manipulated easily and quickly and dependably performs its desired function.

Our invention will be readily understood by reference to the accompanying drawings, forming a part of this specification, in which—

Figure 1 is a fragmentary side elevation of a curtain or the like and the body or object to which it is to be attached, the same being equipped with a fastener embodying our invention;

Fig. 2 is a similar view of the same with the locking member of the fastener in an open position;

Fig. 3 is a vertical section taken substantially on the line 3—3 of Fig. 1;

Fig. 4 is a rear view of the fastener member carried by the curtain or the like when the same is designed to be attached to a solid body, or by the outer curtain when two curtains are designed to be secured together, and

Fig. 5 is an end edge view of the device as shown in Fig. 1.

Referring now to the drawings in detail, numeral 6 designates a curtain or flap, usually of leather, which it is desired to detachably secure to the part 7, which for the purposes of this description may be considered as a solid body, such as a part of a vehicle body, but which may be another curtain or flap.

Fixed to the part 7 is a stud or post 8 which is preferably provided with a curved or dome-shaped end 9 and which also is provided with an annular groove or channel 10.

The fastening device proper is preferably stamped from sheet metal and comprises a flat rear plate 11 and a front plate 12 of corresponding configuration, the latter having in-turned edges 13 to form a narrow chamber between the two plates when assembled. The rear plate 11 is slightly smaller than the front plate 12 whereby, when the two plates are positioned on opposite sides

of the curtain or flap 6 and the rear plate is forced slightly into the chamber between the two plates, the material of the curtain or flap is slightly distorted and forced into 5 said chamber, as shown in Fig. 3, so that when the lugs or ears 14, with which the plate 12 is provided, are forced through the material and bent inwardly to clasp or engage the plate 11, the combined plates are 10 firmly secured to the curtain or flap and to each other.

The rear plate 11 is provided with a preferably circular orifice 15 and the front plate 12 is provided with a correspondingly positioned orifice 16, the edges of the latter being preferably in-turned like the edges of 15 the plate itself to brace and give strength and rigidity to the assembled parts. The orifices are slightly larger than the stud or 20 post 8, whereby this member of the fastener may be readily slipped over or off of said post.

Pivoted to the front face of the plate 12 at 17 is a metal locking strip 18 having a 25 substantially semi-cylindrical portion 19 struck up near the free end thereof and so dimensioned that it will freely pass over the curved end of the post 8, when the latter has been passed through the orifices 15 and 30 16, preferably so snugly fitting over the end of said post as to slightly spring the metal, the semi-cylindrical portion 19 of said strip 18 being relatively positioned for this purpose. Struck down from the sides of the 35 semi-cylindrical portion 19—or left flat by the dies when this semi-cylindrical portion is struck up—are the inwardly directed lips or lugs 20 and 21 the ends of which are adapted to enter the groove 10 in the post 8. 40 As stated, the semi-cylindrical portion 19 of the strip 18 is so dimensioned, and the groove 10 and the lips 20 and 21 so relatively positioned, that the metal of the parts is slightly sprung to firmly hold the strip 45 18 in locking position. While friction alone might be sufficient to retain the parts in locking positions under ordinary conditions, we prefer to provide the plate 12 with a dent or protuberance 22 and the strip 18 with a 50 correspondingly located small aperture 23, the resiliency of the metal causing the dent or protuberance 22 to pass into the aperture 23 and hold the strip 18 in locking position with sufficient force to prevent accidental dislodgment, yet be capable of being easily overcome by manual forces when it is desired to unfasten the curtain or flap.

To enhance the spring tension of the locking strip 18, we provide the plate 12 with a 55 circularly disposed slot 24 and the end of the strip 18 with a lip 25 passing through said slot and slidably engaging the inner face of the plate 12. When the strip is in

locking position, the lip 25 may be yieldingly engaged in a recess 26, and thus still 60 further decrease the possibility of accidental dislodgment.

It is believed that the operation of the device will be readily understood from the foregoing description thereof. It will be 70 apparent that in the fastening operation the strip 18 is swung to the right, as shown in Fig. 2, the fastening member passed over the pin or post 8, and the strip 18 returned to the position shown in Fig. 1. It will also 75 be clearly apparent that the operation of unfastening the curtain or flap consists in merely swinging the strip 18 to the right and removing the fastener.

We have found that a device such as that 80 just described is not only comparatively cheap in cost and easily and quickly manipulated, but is thoroughly dependable in that the parts cannot be jarred out of locking positions under ordinary conditions, and no 85 amount of wear to which the device might be subjected during the normal life of the curtain or flap could result in producing the objectionable "rattle" to which we have referred.

Many modifications of minor details of 90 our improved fastener will doubtless readily suggest themselves to those skilled in the art to which it appertains, and we therefore do not desire to limit our invention to 95 the specific construction herein shown and described.

We claim as new and desire to secure by Letters Patent:

1. A fastener comprising a post adapted 100 to be mounted upon one of two articles to be fastened together and a plate adapted to be secured to the other, said post being provided with an annular groove and said plate having an orifice therein adapted to receive 105 said post, and a locking strip pivoted to said plate to slidably oscillate thereon, said strip having an off-set portion adapted to pass over the protruding post and inwardly directed lips adapted to pass into said groove 110 and engage said post.

2. A fastener comprising a post adapted 115 to be mounted upon one of two articles to be fastened together and a pair of plates adapted to be secured to the other by clamping 120 the latter therebetween, said post being provided with an annular groove and said plates having registering orifices therein adapted to receive said post, and a locking strip pivoted to one of said plates to slidably oscillate thereon, said strip having an off-set portion adapted to pass over the protruding post and inwardly directed lips adapted to pass into said groove and engage said post.

3. A fastener comprising a post adapted

to be mounted upon one of two articles to be fastened together and a plate adapted to be secured to the other, said post being provided with an annular groove and said plate having an orifice therein adapted to receive said post, a locking strip pivoted to said plate to slidably oscillate thereon, said strip having an off-set portion adapted to pass over the protruding post and inwardly directed lips adapted to pass into said groove and engage said post, and means for

yieldingly retaining said strip in locking position.

In testimony whereof we affix our signatures in presence of witnesses.
